US0D1043654S

(12) **United States Design Patent** (10) **Patent No.:** **US D1,043,654 S**
(45) **Date of Patent:** **** Sep. 24, 2024**

(54) **MAGNETIC CARTRIDGE AND LID ASSEMBLY**

(71) Applicant: **Shenzhen Skywin Electronic Co., Ltd.**, Shenzhen (CN)

(72) Inventor: **Huacheng Sun**, Shenzhen (CN)

(73) Assignee: **Shenzhen Skywin Electronic Co., Ltd.**, Shenzhen (CN)

(**) Term: **15 Years**

(21) Appl. No.: **29/814,358**

(22) Filed: **Nov. 5, 2021**

(30) **Foreign Application Priority Data**

Jul. 19, 2021 (CN) 202130456070.9

(51) **LOC (14) Cl.** **14-01**

(52) **U.S. Cl.**

USPC **D14/263**; D14/264
